UNITED STATES PATENT OFFICE.

WILLIAM O. CROCKER, OF NORTH ADAMS, MASSACHUSETTS.

PUMP.

1,118,533.

Specification of Letters Patent.

Patented Nov. 24, 1914.

Application filed July 21, 1913. Serial No. 780,112.

To all whom it may concern:

Be it known that I, WILLIAM O. CROCKER, a citizen of the United States of America, residing at North Adams, in the county of 5 Berkshire and State of Massachusetts, have invented new and useful Improvements in Pumps, of which the following is a specification.

This invention relates to a pump and 10 more particularly to a rotary water pump for general application and specifically adapted for use as an element in an automobile fire pump.

While in many of its broad features my 15 new pump resembles the old pump, by certain changes in the arrangement and construction of the parts and by certain refinements of design I have considerably increased its efficiency and speed without in 20 the least affecting the complexity of its parts.

Among the important advantages of my 25 new pump, I may enumerate the following points: First, the abutments which are swept by the tips of the teeth of the rotors are in my new pump extended inwardly toward each other so as to control the size and shape of the discharge outlet. Second, these 30 abutments, while standardized, for any given pump, as to the shank and the arm contiguous to the pump wall, may vary widely as to the inwardly extending arm, so that by replacing merely the abutments the 35 size and contour of the discharge port may be radically altered.

The result of determining the size and shape of the discharge port by means of replaceable abutments is of far-reaching importance. No adequate method of ascertaining the proper shape for the exhaust passage of a rotary pump is known except that of "cutting and trying." In all rotary pumps except mine this must be done by rebuilding the pump or at least the pump casing. This is tedious and almost prohibitively expensive. In my pump the abutments only need to be altered. But this is not the sole advantage of my device. The best shape and size for the discharge passage depends upon the class of work which the pump does. When, as is often the case, the pump is used at one time to furnish a small high pressure stream, and at another time a large low-pressure stream, discharge passages of different design are desirable. Heretofore if the pump user demanded effi-

ciency for both high and low-pressure work he bought two pumps. With my pump he only needs two sets of abutments.

Other advantages will appear as the detailed description to follow proceeds.

In the drawings.—Figure 1 is an elevation of my pump with one of the casing plates thereof removed; Fig. 2 is a similar partial view showing a variation in the arrangement of the abutments; Fig. 3 is a plan view of the pump; and Fig. 4 is an elevation of the casing showing the baffle-plates.

1 is the casing comprising suitable side, top, and bottom plates bolted together substantially as in the old construction. The two side plates of the casing, 2 and 3, are provided with bearings for the shafts 4 and 5,—these shafts being provided at one end with intermeshing gears 6 and the shaft 5 being provided at the other end with a driving pinion or gear 7. It will thus be seen that the drive of the pump proper is effected entirely from without the casing and that therefore the rotors to be hereinafter described have no driving or pushing action one upon the other whatever. Each of the casings 2 and 3 is provided with a baffle-plate or baffle-section 8. This element of the machine may comprise a separate plate in the nature of a washer, but is preferably made integral with each side casing, as shown in Fig. 4. In contour it comprises two substantially key-shaped parts 9 connected as shown at 10. Its form is such that the rotors 11 and 12 being at all times in contact upon either side with its baffle-plates and the abutments 13 and 14, divide the interior of the casing into two non-communicable chambers, one thereof comprising that part of the casing lying principally beneath and to the right and left of the baffle-plate 8 and accessible through the inlet port of the pump, and the other part comprising, broadly, that part of the casing lying above and between the projections 9 of the baffle-plates.

It is to be particularly noted that in the operation of the pump there are always two teeth of the rotors 11 and 12 meshing over section 10 of the baffle-plates and moreover that there is always at least one tooth of the corresponding rotors 11 and 12 lying over the extensions 9 upon the baffle-plates 8. By this construction, while I have made a perfectly sealed and water-tight pump, I have made it possible to machine only so

much of the interior of the side casings as concerns the baffle-plates 8, the finish of the rest of the interior of the casing being immaterial.

5 The top of the casing in my new construction (see Figs. 1 and 4) is provided with a pair of key-ways 13 and 16 between which is located the outlet-port 17. In these key-ways slide the shanks 18 and 19 of the 10 abutments 13 and 14 which coöperate with the rotors. These abutments are set to accurately adjusted position by the set-screw 20, as shown. The abutments 13 and 14 are of 15 substantially T-form and their shanks alone are engaged in key-ways in the casing.

The abutments 13 and 14 extend toward each other, partly overlapping the opening in the casing through which the pump discharges, so that the size and shape of the 20 outlet is determined by, and may be altered by changing, the contour of the inward arms of the abutments.

The rotors 11 and 12 are in my new pump formed with teeth cut at the cycloidal 25 curves, these curves being so designed that in the operation of the pump the intermeshing portions of the two engage at all times with a rolling and not a scooping, grinding or sliding contact. It is obvious that this 20 improvement results in a tremendous diminution of wear upon the parts, for it will be readily apparent that inasmuch as the two shafts 4 and 5 are positively driven from without the casing and that therefore

the rotors have themselves no driving action 35 one upon the other in operation, the pump runs smoothly along without the slightest friction between the rotors.

Fig. 2 shows a modification adapted for a 40 still wider range of control by means of variation in the inward arms of the abutments.

Many modifications may be made in the precise form and arrangement shown, and all such as do not depart from the spirit 45 and scope of my invention I purpose to cover in the following claims.

What I claim is:—

1. A rotary pump comprising in combination, a casing having inlet and outlet 50 openings, parallel side plates and a connecting wall, shafts having rotors thereon, provided with intermeshing teeth, abutments coöperating with the rotors and having inwardly extending arms which partly overlap the discharge opening in the casing and determine the discharge port of the pump. 55

2. A rotary pump, comprising abutments coöperating with the rotors and overlapping the exhaust opening in the casing, and determining the discharge port. 60

3. A rotary pump having replaceable abutments for determining the outlet port.

WILLIAM O. CROCKER.
